UNITED STATES PATENT OFFICE

HUGO JUNKERS, OF DESSAU, GERMANY

DISTRIBUTION OF PULVERULENT MATERIAL FROM AIRCRAFT

Application filed October 5, 1925, Serial No. 60,693, and in Germany July 3, 1925.

My invention refers to a flying machine adapted for the distribution of insecticides, germicides and the like. It is an object of my invention to provide means whereby this [5] distribution can be effected in an easier and more perfect manner than has hitherto been possible.

Up till now the distribution of insecticides, germicides and the like from aerial craft has 10 been practised either by emptying a receptacle containing the pulverulent masses over the sides of the machine, the distribution of the material being left to the propeller wind or else a certain automation and distribution was effected, partly by the action of the 15 propeller wind and partly by the static pressure acting on the material in the receptacle. Both these methods involve certain drawbacks. If the receptacle is merely emptied over the side of the craft, no uniform distribution can be obtained, the greater part of the material clogging together and dropping on the ground in lumps. If the material is first acted upon by the static pressure 20 introduced into the receptacle and is then distributed by the propeller wind, the material is subdivided so finely that it has become necessary for the craft to travel at very low altitudes, whereby the craft is endangered and 25 the distribution can only be effected on even ground. A further drawback which adheres to this method is occasioned by the moisture contained in the air which, when the material is atomized by static pressure, favors the 30 clogging together of the material owing to the fact that most substances used for this purpose are highly hydroscopic.

According to the present invention I obviate these drawbacks by providing the aerial 35 craft with means whereby the material in question is atomized mechanically and preferably in dependency upon the traveling speed of the craft, the propeller wind being utilized for distributing the material thus atomized.

By proceeding in this manner, it is possible to transfer the material from the receptacle to a point where the propeller wind and gravity can act upon it for distribution in a sufficient state of subdivision. On the other hand

the mechanical, easily controllable operation of the atomizing means allows covering the ground with the material in question in an entirely uniform manner. By means of special devices the quantity of material deposited on the ground per unit of area can be adjusted in correspondence with the particular purpose and material. 55

Preferably the device for practising the novel method comprises two main parts, viz 60 a receptacle, preferably mounted in the hull or body of the flying machine or in the cabin of an airship, and an atomizing and distributing device.

I am thus enabled, when employing a different type of flying machine, to merely exchange the receptacle, while, if a different kind of material shall be distributed, merely 65 the atomizing device need be exchanged.

In the drawings affixed to this specification 70 and forming part thereof a flying machine embodying my invention is illustrated diagrammatically by way of example;

Fig. 1 being a side elevation of this machine, while

Fig. 2 is a vertical section of the distributing device proper drawn to a larger scale.

Fig. 3 is a horizontal section drawn to a smaller scale on the line III—III in Fig. 2.

Referring first to Fig. 1, 1 is the hull or 80 body of the flying machine and 3 is the receptacle containing the material and which is mounted in the hull or body, an opening 4 provided with a suitable cover serving for filling the receptacle. To the funnel-shaped bottom of the receptacle 3 is connected the conduit 6 leading to the distributing device proper, this conduit extending in oblique direction. 85

In order to detach from the inner walls of 90 the receptacle such material as may adhere to it, special means (agitators, cords or the like) arranged to be operated from the pilot's seat 8 can be provided the quantity of material distributed per unit of area can be varied by 95 means of a spindle 9 mounted in front of the pilot's seat and which by means of an intermediate shaft 22 and bevel gearing 23 acts on the distributing device proper illustrated more particularly in Fig. 2. This device com- 100

prises a vertical extension 10 secured to the oblique conduit 6 and the rotor 14 loosely mounted for free rotation on a rod 12 extending in vertical direction across the conduit 6 and projecting from the upper side thereof. Cup-shaped blades 13 are mounted on the circumference of the wind driven rotor 14 which has the form of a double cone, the top part of which is set with radial ledges 15 projecting into the extension 10. During each revolution of the rotor the ledges 15 carry along with them a predetermined quantity of the pulverulent material and force it through the gap between the bottom edge of the extension 10 and the circumferential top edge of the rotor 14. In order to adjust the width of the gap the rotor 14 can be lifted and lowered respectively by means of the bevel-wheel 20 governed by the spindle 9 and shaft 22, the hub 24 of this bevel-wheel having the form of a nut acting on the threaded top end 21 of the rod 12, which is secured against rotation at 16. By lifting or lowering the rod and the rotor the width of the distributing gap is varied. At the lower edge of the extension 10 is mounted a ring 17 which projects into an annular notch of a ring 18 mounted on the peripheral portion of the rotor 14, this ring serving for properly defining the gap and if necessary for braking the rotor.

I wish it to be understood that I do not desire to be limited to the exact details of construction shown and described for obvious modifications will occur to a person skilled in the art.

I claim:—

1. In a flying machine, a receptacle for pulverulent material, a tubular conduit extending from said receptacle downwards, an air-impelled rotary distributor at the lower end of said conduit and means for adjusting the position of said distributor relative to said conduit.
2. In a flying machine, a receptacle for pulverulent material, a tubular conduit extending from said receptacle downwards, an air-impelled rotary distributor at the lower end of said conduit, means on said distributor and extending into said conduit for carrying along predetermined quantities of the material in said conduit, and means for adjusting the position of said distributor relative to said conduit.
3. In a flying machine, a receptacle for pulverulent material, a tubular conduit extending from said receptacle downwards, an air-impelled rotary distributor at the lower end of said conduit and means operable from a distance for adjusting the position of said distributor relative to said conduit.
4. In a flying machine, a fuselage, a receptacle for pulverulent material supported by said fuselage, a pilot's seat in said fuselage, a tubular conduit extending from said

receptacle through the walls of said fuselage, a rod extending vertically below said fuselage, an air-impelled rotary distributor loose on said rod at the lower end of said conduit and means operable from said pilot's seat and operatively associated with the upper end of said rod for adjusting the position of said distributor relative to said conduit.

In testimony whereof I affix my signature.

HUGO JUNKERS.
